UNITED STATES PATENT OFFICE.

ALVY W. KLINE, OF OKLAHOMA, OKLAHOMA.

COMBINATION POINTER AND JOINTER FOR STONE AND BRICK LAYERS.

1,014,650.

Specification of Letters Patent.

Patented Jan. 16, 1912.

Application filed April 15, 1910. Serial No. 555,627.

To all whom it may concern:

Be it known that I, ALVY W. KLINE, a citizen of the United States, residing at Oklahoma city, in the county of Oklahoma and State of Oklahoma, have invented certain new and useful Improvements in a Combination Pointer and Jointer for Stone and Brick Layers, of which the following is a specification.

10 My invention relates to a combination pointer and jointer for stone and brick layers, in which a small trowel-blade has an offset, tapered and bent handle to point and smooth the joints between the stones or 15 bricks in walls.

The objects of my invention are to combine in one tool a pointer and a jointer as a matter of convenience and economy. I 20 accomplish these objects by the mechanism illustrated in the accompanying drawings, forming a part of this specification, in which:

Figure 1 is a side elevation of my device; Fig. 2 is a plan view of the device; Fig. 3 25 shows a portion of a wall in elevation and the device, in part, in operation, Fig. 4 shows the device, in part, being used as a jointer.

Similar letters refer to similar parts in 30 the several views.

Referring to the drawings A designates a steel blade having a blunt point *a*, and oval edges *b* varying in degrees of convexity to adapt it to scrape off the surplus mortar in 35 pointing the various joints between the courses of stone or of brick in walls, it being customary to leave the mortar in the joints below the plane of the wall and also smooth. See Fig. 3. To make the device 40 more convenient in operation the portion of the blade A, opposite its point has an upwardly and rearwardly extending shank B, terminating in a rearwardly extending cylindrical handle C, being slightly enlarged 45 at *c*, intermediate its ends and having its rear end gradually tapered and downwardly bent. See Fig. 1.

The device is preferably, constructed from a single piece of metal.

In the construction of stone and brick 50 walls it is quite common to point the joints in the walls with colored mortar to show contrast and break the monotony of the appearance of the wall.

In operation, the blade A is used in filling the joints *h* of the wall with mortar and where little importance is attached to the finish, the edge *b* of the blade A is moved along the joint, transversely thereto, to remove the surplus mortar to a degree below the plane of the wall, varying according to the portion of the edge *b* of the blade used, as at *d* and *e*, Fig. 3, the greater the convexity of the edge of the blade used the deeper will be the depression of the mortar 65 in the joint. In walls where the corners *f* of the stones *i* are cut away as at *f* in Fig. 4 and where the bricks *j* have beveled edges as at *g*, Fig. 3, after the surplus mortar is removed from the joint *h* by the blade A the 70 device is reversed and the convex portion of the handle C, as at *C'*, or *C''*, is drawn along in the joint pressing the mortar firmly into the joint and leaving its surface smooth. See Figs. 3 and 4. On account of the handle 75 *C* being bent and tapered it is adapted to joints of varying sizes within the range of ordinary practice, as at *C'* and *C''* being cross sections on lines *xx* and *x'x'* Fig. 2.

Having thus described my invention, what 80 I claim as new and useful and desire to secure by Letters Patent, is—

A combined pointer and jointer, in one piece, comprising a blade, a handle integral therewith, and of varying cross-sectional 85 areas at different points, and having the free end portion thereof gradually tapering, whereby the reduced end may be used for pointing.

In testimony whereof I affix my signature in presence of two witnesses.

ALVY W. KLINE.

Witnesses:

MAGGIE KLINE,
A. D. MARBLE.
